UNITED STATES PATENT OFFICE.

CARL J. E. WAXBOM, OF COLUMBUS, OHIO, ASSIGNOR TO THE JEFFREY MANUFACTURING COMPANY, A CORPORATION OF OHIO.

LOCOMOTIVE

1,085,715.

Specification of Letter Patent. Patented Feb. 3, 1914.

Application filed July 29, 1911. Serial No. 841,215.

To all whom it may concern:

Be it known that I, CARL J. E. WAXBOM, a citizen of the United States, residing at Columbus, in the county of Franklin and State of Ohio, have invented certain new and useful Improvements in Locomotives, of which the following is a specification, reference being had therein to the accompanying drawing.

10 This invention relates to locomotives and more especially to industrial locomotives of the type adapted for use in the yards and shops of manufacturing plants, or in and about coal or similar mines.

15 The object of the invention is to provide a locomotive having improved power transmitting mechanism between its motor and the drive wheels.

Other objects will be apparent from the 20 following specification.

In the accompanying drawings I have shown one embodiment of my invention, but it will be understood that the construction shown is susceptible to various changes and 25 modifications. For instance, another type of motor may be substituted, if desired, for the internal combustion engine which is shown.

Of the drawings, Figure 1 is a side elevation of a locomotive embodying my invention; Fig. 2 is a plan view; Fig. 3 is a longitudinal cross sectional view taken along the line 3—3 of Fig. 1; Fig. 4 is a fragmentary longitudinal cross sectional view through 35 the gearing at one end of the locomotive. Fig. 5 is a fragmentary cross-sectional view taken along the line 5—5 of Fig. 4.

Referring to the drawings, 1 represents the locomotive frame which is mounted in 40 the usual manner upon axles 2, 2^a, which are secured to and supported by the track wheels 3, 3^a.

4 represents the motor for driving the locomotive. In the drawings I have represented this motor as an internal combustion engine, as I consider this form of motive power especially adapted for this class of work. It will be understood, however, that a motor of any of the other usual types may 50 be substituted if preferred. When an internal combustion engine is used a tank 4^a

for gasoline or other fuel is provided and a tank 4^b for cooling water. The motor 4 is provided with a longitudinal power shaft 5 which is preferably located near the center 55 of the locomotive. At the ends of the shaft 5 and substantially in alinement with it are other shafts 6 and 6^a. Each of these shafts is connected to the shaft 5 by means of a flexible coupling indicated by 7. Each of the 60 couplings 7 is constructed to transmit power from one shaft to the other, but to permit relative movements of the shafts to positions out of alinement with each other.

The particular form of coupling which I 65 have illustrated comprises disks 7^a and 7^b secured respectively to the ends of the shaft 5 and the shaft 6 or 6^a as the case may be. Between the disks 7^a and 7^b there is mounted a plate or equivalent element 7^c which is 70 provided with four equally spaced radial notches or slots. Pins or rollers 7^d, 7^d on the disk 7^b extend into one pair of opposite slots. Other pins or rollers 7^e, 7^e on the disk 7^a extend into the other slots. As the pins 75 are all free to move in their slots relatively to the element 7^c, freedom of movement of the two shafts within reasonable limits is permitted.

Referring now to the construction at one 80 end of the locomotive, as, for instance, the right-hand end as viewed in the drawings, 8 and 9 represent two meshing spiral gears, the larger of which 8 is keyed to the axle 2, and the smaller of which 9 is rotatably 85 mounted upon the shaft 6. 10 is a casing surrounding the gears 8 and 9 and having bearings at 11 and at 12 on the axle 2. In order to hold the casing vertical and prevent its swinging about the axle, an upstanding 90 forked arm 10^a is provided which embraces a transverse bar 10^b which is secured at its ends to the locomotive frame. The shaft 6 at a point adjacent the coupling 7 has a bearing in the upper part of the casing 10. 95 The other end of the shaft 6 has a bearing in the sleeve 13 which is secured to or formed as a part of the gear 9 and which has a bearing in the casing 10 at a point opposite to the bearing for the shaft 6. A 100 friction clutch 14 is provided for connecting the shaft 6 and the sleeve 13. The clutch is

preferably of the disk type and comprises two alternately arranged series of disks. The disks of one series are connected at their centers with the shaft 6 and the disks of the other series are connected at their peripheries with the flange 15 secured to the sleeve 13. By means of a suitable pivoted cam 16 controlled by a lever 16^a pressure may be transmitted to the disks to force them into close engagement with each other, through the collar 17, the ball bearing 18 and the plate 19.

The construction at the other end of the locomotive is similar to that which has been described. It differs from it, however, in that the gearing 8 and 9^a between the shaft 6^a and the axle 2^a is constructed to cause rotation of the axle 2^a in the opposite direction from that of the axle 2. The gear 9^a may be connected with the shaft 6^a by means of the clutch 14^a which is controlled by the cam 16^b through the lever 16^c. The two levers 16^a and 16^c are connected by a link 21 so that they may be simultaneously operated by means of a handle 22 adjacent the operator's seat, which may be formed, if desired, as an extension of the lever 16^c. The levers may be secured in adjusted positions by means of a latch which engages with notches in the segment 23. The cams 16 and 16^b are so constructed that both of the clutches are disengaged when the handle 22 is in central position. When the handle is moved in one direction, toward the right, for instance, the clutch 14 is engaged. When the handle is thrown toward the left the clutch 14^a is engaged. At the end of the shaft 6^a there may be provided a crank 20 by means of which the shaft may be manually rotated to start the engine. The drive-wheels 3, 3^a at each side of the locomotive are connected for synchronous rotation by suitable connecting rods 24, 24. Suitable braking mechanism 25 is provided for the wheels 3, 3^a. This mechanism is controlled by a hand wheel 26.

In operation the motor 4 is first started, both clutches being disengaged. To cause the locomotive to move in one direction, toward the left, for instance, the handle 22 is moved toward the left to throw the clutch 14^a into engagement. Power is then transmitted through the shaft, through the clutch and the spiral gearing 9^a, 3^a to the axle 2^a and the track wheels 3^a. Inasmuch as the track wheels are all connected together by means of the rods 24 the whole weight of the locomotive is available to provide tractive force. It will be understood that when the locomotive is operating as just described the gear 9 will be rotated freely in the reverse direction by means of the gear 8. To drive the locomotive in the other direction the handle 22 is moved toward the right and the clutch 14 is thrown into engagement. Power

is then transmitted through this clutch and through the spiral gearing 9, 8 to drive the axle 2 and the wheels 3, in the other direction. The gear 9^a will be rotated in the reverse direction by the gear 8^a.

It will be observed that by my invention I have provided a very simple means whereby the locomotive may be caused to move in one direction or the other, or may be brought to a rest by the simple movement of a single lever.

What I claim is:

1. In a locomotive, the combination of a frame, axles and track-wheels for the frame, a longitudinal shaft, a motor for rotating the shaft, a gear revolubly mounted on the shaft, a manually controllable clutch for operatively connecting the gear wheel with the shaft, a gear wheel rigidly connected with one axle and arranged to mesh with the gear on the shaft, the said gearing serving when the clutch is engaged to rotate the said axle in one direction, a second gear revolubly mounted on the longitudinal shaft, a second manually controllable clutch for operatively connecting the second gear with the shaft, and a second gear wheel rigidly connected with the other axle and arranged to mesh with the said second gear on the shaft, the said gearing serving when the second clutch is engaged to rotate the second axle in the direction opposite to the direction of rotation of the first axle when the said first clutch is engaged.

2. In a locomotive, the combination of a frame, axles and track wheels for the frame, a longitudinal shaft axially fixed at its ends with respect to the axles, an internal combustion motor for rotating the shaft, two gears revolubly mounted on the said longitudinal shaft, two manually controllable clutches for operatively connecting either of the said gears with the shaft, gear wheels rigidly connected respectively with the axles and arranged to permanently mesh respectively with the said gears on the shaft to drive either axle when the corresponding clutch is engaged, and a crank at one end of the shaft for rotating it to start the motor when both clutches are disengaged.

3. In a locomotive, the combination of a frame, axles and track wheels upon which the frame is resiliently mounted, a longitudinal shaft comprising three sections, the center section being mounted upon the frame and the end sections being mounted, respectively, on the axles, couplings between the sections adapted to transmit power but to permit relative movements of the sections to non-aligning positions, a motor connected to the center section of the shaft for rotating the shaft in one direction, power transmitting mechanism between one end section and

one axle for rotating the axle in one direction, the power transmitting mechanism comprising permanently meshing gearing and a manually controllable clutch, and a power transmitting mechanism between the other end section and the other axle for rotating it in the other direction, the power transmitting mechanism comprising perma-

nently meshing gearing and a manually controllable clutch.

In testimony whereof I affix my signature, in presence of two witnesses.

CARL J. E. WAXBOM.
